UNITED STATES PATENT OFFICE.

WILLIAM PLATTS KELLETT, OF BRANTFORD, ONTARIO, CANADA.

FREIGHT-TRANSPORTATION MEANS.

Application filed August 12, 1926. Serial No. 128,846.

The principal objects of the invention are to enable shippers to handle packaged freight or other parcels with the least possible damage and to reduce the cost of handling the goods by providing containers that may be very easily moved about a warehouse or handled on trucks and securely retained on the deck of an open railway car.

10 A further object is to facilitate the distribution of goods and still further, to enhance the features of rail transportation as against truck haulage over long distances.

The principal features of the invention 15 consist in the novel arrangement of merchandise containers upon a railway car and in providing means for absorbing the violent longitudinal shocks incident to the handling of freight cars whereby the goods 20 in the containers are preserved from breakage.

In the accompanying drawings, Figure 1 is a side elevational view of a freight car showing the novel construction and arrangement of a plurality of merchandise containers held thereon.

25 Figure 2 is an enlarged plan view of one end of a flat car showing the arrangement of the spring buffers.

30 Figure 3 is a side elevational view of the end of the car showing the buffer in a raised position.

Figure 4 is an end elevation showing the buffers in a raised position and also showing the means for holding the containers in 35 position transversely.

40 Figure 5 is an enlarged elevational detail of the means for securing the containers on the trucks illustrated in Figure 1.

It has been ascertained that in the handling of package freight enormous losses by breakage are due to the shocks occasioned by the shunting and stopping and starting 45 of trains.

The principal factor in the cause of the damage through shocks is the rigidity of the structure of the standard freight cars. According to the present invention the freight 50 is packed in containers which are mounted upon rollers and placed on a railway car and are allowed a certain freedom of movement under control of spring cushioned devices so that the shocks imparted to the 55 car are absorbed by the spring cushioning devices to such an extent as to ensure the

safety of the goods in the containers from damage from this cause.

In the form of the invention herein shown, the flat car 1 is provided with longitudinal trackways 2 of a suitable design and suitable flaring guides 3 are arranged at each end thereof. The containers 4 are built of a sturdy structure of any suitable design and are mounted upon rollers 5, preferably arranged in pairs at the extremities and having two other pairs disposed intermediate of the length of the container, the four sets of rollers being preferably equally spaced apart and the distance between such 70 rollers being such that when the containers are moved from one car to another the end rollers will reach the trackways of the next succeeding car from which the container is being moved. The container is 75 thus relieved of injurious stress and a smooth continuous movement is ensured in the movement of the containers from car to car.

Each container is provided with a suitable type of spring buffer 6 at the ends, preferably arranged in pairs and these buffers are adapted to engage the adjacent containers. Adjustable spring buffers 7 are arranged at the ends of the cars to engage 85 and hold the containers in place upon the car.

Each container is provided with a flanged plate 8 extending longitudinally on each side having the flange 9 at the lower edge 90 thereof extending parallel with and close to the deck of the car.

Longitudinally arranged guides 10 each having a horizontal slot 11 open at the ends are rigidly secured to the deck of the car 95 and are adapted to receive the flanges 9 of the plates 8. Said flanges are adapted to move freely longitudinally in the guides 10, which guides extend substantially the full length of the car but they hold the container 100 securely to the deck of the car preventing side sway or tilting, but when the car is suddenly stopped or started the impact is received and absorbed by the spring buffers, the containers being free to move longitudinally back and forth on the deck in the shock-absorbing movement.

The type of spring compression buffer used on the ends of the containers have preferably a spring compression of about 3 110 inches and the end buffers on the flat cars preferably have a spring compression of $\frac{4}{3}$

inches so that where there are three containers on a flat car there will be a spring compression of approximately from 15 to 20 inches.

5 It will be readily understood that such a provision will be such as to relieve the contents of the containers from injurious shock and an enormous saving in the damage to goods in transportation will be effected.

10 It will be understood that the end buffers 7 must be arranged so that they may be moved out of the way so that the containers may be placed and removed with freedom and in the construction shown these buffers 15 are in the form of bracket members having tubular portions 12 slidably arranged on a rigid bar member 13 secured to a bracket 14. A tubular bracket 15 journals the outward end of the tubular portion of the 20 buffer and a compression spring 16 is enclosed therein to receive the end shocks.

The brackets 14 and 15 are mounted in recesses 17 below the deck surface so that the buffers may be swung downwardly and 25 housed in the recesses to allow the containers to move over the same freely.

The upper ends of the buffers are provided with jack screw bumper ends 18 which are adapted to align with the spring buffers 6 30 on the containers and by means of the threaded adjustment thus provided any slack caused by variation in the length of containers or buffers may be taken up to ensure the containers being held from loose 35 play endwise of the car.

For certain classes of package freight or parcel post the containers may be provided with different sized compartments to enable the more ready and safe handling of small 40 packages or container trucks 19 which are more fully described in my co-pending application 221,084, filed September 21, 1927 and illustrated in Figure 1 may be provided upon which are mounted smaller sized containers 20. The containers 20 are preferably provided with rollers and they are so arranged that the containers may be moved 45 transversely of the trucks.

50 Flanged holding plates 21 similar to the guides 10 are arranged on the top of the truck and engage the flanges 22 on the containers 20 and these containers may be held from lateral movement by locking pins 23 inserted through holes in the flanges and 55 flange plates 22 and 21.

It will be readily understood that this invention must not be limited to the details of structure as many variations in such may be made without departing from the spirit 60 of the invention.

This invention has another very important phase, namely, that in its application the expense of maintenance in rolling stock and locomotive equipment is very greatly 65 reduced. The dead load on the locomotive,

in the starting of a train, is very greatly relieved by providing longitudinal resiliency in the connections between the goods containers and the cars and the force expended in the initial movement and absorbed by the springs immediately reacts to propel the load in the direction of movement and effectively assists the tractive effort of the locomotive. This condition ensures the starting of heavily loaded trains with ease 70 and the structure of the rolling stock will be considerably relieved from stress. 75

What I claim as my invention is:

1. A freight transportation means, comprising a railway car, separate containers 80 movably mounted on said car, and means movable longitudinally of said car engaging said containers and cushioned to absorb the longitudinal shocks imparted to the railway car.

2. A freight transportation means, comprising a railway car, separate containers movably mounted on said car, compression buffers arranged on the ends of said containers, and compression buffers arranged at 90 the ends of the railway car to engage the ends of the end containers.

3. A freight transportation means, comprising a railway car, separate containers movably mounted on said car, and spring 95 buffers pivotally mounted at the ends of the railway car to be swung into or out of the path of movement of the containers and adapted to engage the containers to limit their longitudinal movement on the car, 100 said buffers being arranged to be swung downwardly clear of the containers to allow their removal from the car.

4. A freight transportation means, comprising a railway car, separate containers 105 movably mounted on said car, rigid supports mounted on the ends of the car, bracket members pivotally and slidably arranged in said rigid supports, and compression springs engaging said slidable members.

5. A freight transportation means, comprising a railway car, separate containers movably mounted on said car, bracket members pivotally and slidably supported at 115 the ends of the car, cushion springs engaging said slidable members, and jack screws threaded in the free ends of said pivotal members adapted to engage the containers.

6. A freight transportation means, comprising a railway car, separate containers 120 movably mounted on said car, recesses formed in the deck of the car at the ends, pivotal spring buffer members mounted in said recesses and adapted to be housed there-in below the surface of the deck.

7. A freight transportation means, comprising a railway car having longitudinal trackways, flanged guides rigidly secured to the car and arranged parallel with said 125

trackways, separate containers having rollers engaging said trackways, flanged members extending longitudinally of said containers and slidably engaging in said flanged 5 guide-ways, and resilient means for absorbing longitudinal movement of said containers.

8. A freight transportation means, comprising a railway car having longitudinal 10 trackways, flanged guides rigidly secured to the car and arranged parallel with said

trackways, separate containers having rollers engaging said trackways, flanged members extending longitudinally of said containers and slidably engaging in said flanged 15 guide-ways, spring buffers arranged on the ends of said containers, and removable end buffers at the ends of the car adapted to hold said containers in engagement with said longitudinal guides.

WILLIAM PLATTS KELLETT.
